UNITED STATES PATENT OFFICE.

MERRITT AUGUSTUS WILLIAMS, OF NORFOLK, VIRGINIA.

AUTOMATIC MECHANICALLY-OPERATED OIL BURNER.

Application filed May 5, 1925. Serial No. 28,145.

This invention relates to improvements in automatic mechanically-operated oil burner, particularly in the provision of a solid metal burner nozzle.

5 The object of this invention is to provide a burner nozzle designed and constructed to permit of a perfect operation, having complete control in equalizing and adjusting.

10 A further object of this invention is to provide an oil burner adapted as an atomizer and evaporator, the combination necessary to properly burn cheap oil, at the same time this invention provides means for maintaining a proper temperature thereby preventing 15 overheating of the oil.

Another object of this invention is to provide an oil burner which may be easily adapted to various types of grates and fire boxes in combustion chambers. Under ordinary conditions this invention may be embodied in three special designs which are named for convenience, rectangular, horizontal and perpendicular types their objects 25 will appear in the description and claims as follows:

In the drawings,

Fig. 1, represents a sectional, vertical elevation view of the solid burner nozzle showing the air, oil and spray ducts in section. 30 This view is of the vertical type.

Fig. 2, designates a plan view in section of the burner nozzle taken on line 2—2 of Fig. 1.

Fig. 3, is a sectional plan view taken at 35 line 3—3 of Fig. 1.

Fig. 4, illustrates a section plan view taken at line 4—4 of Fig. 1.

Fig. 5, represents a sectional end view of a burner nozzle taken at line 5—5 of Fig. 6. 40 This view represents a modification in form of Fig. 1.

Fig. 6, represents a side view of a burner slightly modified in form over Fig. 1.

Figs. 7, 8, 9 and 10 illustrate views of a 45 burner nozzle of a slightly modified form over Fig. 1.

These burners may be called the rectangular type, having air ducts 2 and oil ducts 3 so arranged that, leading from the air duct 2 is an air spray tube 5 extending to the oil spray opening 6.

Numeral 1 designates the solid metal body of the oil burner nozzle adapted for various types of combustion chambers hav-

ing an air duct 2, near the top of the body, 55 the air duct 2, being about eight times the cross section of the oil duct 3 which is located between the air duct 2, and the base of the burner body 1. Leading from the air duct 2 is an air spray tube 4 having an 60 extension 5 leading to the oil spray opening 6. Numeral 7 represents a duct in the body 1 adapted as an over-flow for the oil, the over-flow being caught in the receptacle and support located at convenient 65 points near the burner. As an auxiliary means for keeping a constant temperature on the burner, body 1, the gas pilot 8 is adapted for use, either by extending the 70 gas line through an opening 9 in the burner body 1, and suitably fastening the line therein to avoid leakage of oil as at 10 or 11, or by any other means adapted to make use of a gas pilot for the purpose herein-after described. The form of oil burner 75 nozzle disclosed in Figs. 5 and 6 may be termed the horizontal type, having an air duct 2, and the oil duct 3, with the oil spray opening at 6.

The burner body is designed with the 80 necessary openings for receiving tap screws as at 12, 13 and 14, and various lugs such as at 15 and 16 may be made a part of the burner body as supports or otherwise, 85 wherever needed.

In operation this invention provides an automatic mechanical oil burner highly efficient and inexpensive. The burner nozzle being made of solid metal, is practically indestructible and the design and construction 90 permits of a perfect operation. The nozzle may be easily designed in shape to conform with any angle of fire box or design of boiler, each nozzle having its special drip-pan for overflow in case of emergency. The construction of the burner adapts it for any suitable fire box, grate, or substitution for a grate, no part of the boiler being sealed up or fastened in any way and from the fact that the nozzle is ordinarily easy of access, it can be regulated and adjusted for perfect mixture of oil and air, thereby assuring a complete combustion free from smoke and carbon and general loss of heat to chimney. 95 With this burner nozzle a tank heater and heating boiler may be operated by one equipment.

The three types of burners described in

- this application have the same principles of operation and each is made from a single solid metal casting in size, shape and design for different combustion chambers. From numerous tests it has been found that this burner located on the grate of the combustion chamber is protected by the air circulation of the ash pit and also protected by certain provisions in this invention making the burner unit practically indestructible. Obviously, using oil for fuel, there is no heat generated in the ash pit. The protection of the operation exposed in the combustion chamber comprises in part an air duct 2, located near the top of the metal body portion of the burner. These air ducts are designed ordinarily having approximate cross sectional areas as follows:
- For the rectangular type 7 cubic inches; horizontal type 11 cubic inches and perpendicular type 20 cubic inches. It is estimated under ordinary conditions of operation that a minimum volume of 2 cubic feet of air per minute will be circulated through these air ducts. Centered between the air duct and the base of the burner is placed an oil duct proportioned approximately to $\frac{1}{8}$ of the air duct. It is determined from tests that the air and oil give, under suitable conditions, perfect combustion when mixed. Also, it has been found from experiments, that oil if heated beyond a certain temperature, will produce a scum which forms a crust or solid detrimental to efficient operation. This invention therefore, provides an air duct as a cooling member adapted to prevent the overheating of the oil, automatically the air will absorb the heat for valuable purposes of mixing at point of discharge with the oil that is circulated through the oil duct at the minimum rate of $\frac{1}{2}$ gill per minute. The oil usually reaches the discharge point by means of gravity and suction, the air under pressure passing through and over the oil, both at proper temperature, forming therefore a suitable spray for complete combustion.
- As an auxiliary means for maintaining a proper temperature on the burner a gas pilot may be utilized as clearly disclosed in the Figure 1 at 11. The heat from the gas pilot serves the purpose of keeping the mixture at point of discharge ready for proper combustion.
- The oil in this system is supplied through a tube the minimum size of which is $\frac{7}{16}$ of an inch in diameter eliminating the liability of stoppage and allowing the use of oils of low gravity. It is of course, recognized that when air and oil are heated they should be as near the combustion chamber as possible. In this invention, the burner and mixture are both directly inside the combustion chamber. There are a number of advantages gained by the use of this invention, some of

them may be named as follows: Any fluid oil may be burned, the large oil duct $\frac{7}{16}$ of an inch making it impossible for any foreign matter or substance to lodge or choke the duct. The outflow from the oil duct is located below the air duct, thereby preventing any possibility of oil reaching the air duct, the manner in which the combustion mixture is made, controlled, directed and fired, furnishes the most economical method for operating oil burners at present known. The ease of directing the location and distance of travel of the flame permits of omitting all refractory substances such as fire brick, etc., thereby permitting the confining of the fire to any part of the combustion chamber or upper flues. It is recognized that each unit of heat expended in the ash pit is heat wasted, this invention permits the location of the burner on the grate, thereby making it possible to apply the heat to the most desirable portion of any heater. By operating the control valves which are located outside of heater, and not shown in the drawings of this application, the fire travel can be regulated to any point desired. The scope of control being measured by the inch which secures the minimum loss of heat to the chimney. From experiment it has been found that by making use of the advantage derived from control of the burner disclosed in this application, the flame may be directed to the upper flues of heater thereby giving instant circulation to portions or rooms desired to be heated, this results in a system which may be called an instantaneous heater. With the fire centered in the heater to the point or points of supply outlet, the capacity of the heater is increased thereby $33\frac{1}{3}\%$. When the temperature of the water in the upper third of the water heater has reached approximately 140 degrees, and circulated through to each unit of the system, the water in the bottom third part has only slightly changed temperature. From the retort feature, a mixture of heated air and oil, and the perfect atomizing feature the combustion is ideal, in that there is no smoke, soot, carbon or odor. Furthermore, when the automatic control cuts off, the burner will cut out immediately, thereby leaving no residue mixture to slowly burn and carbonize. A further advantage of this invention obviously lies in the fact that the duct described as an air duct has a dual operation, in that it operates with either steam or air.

It may also be stated that the air when passing from the air spray tube of this invention, creates a vacuum in the oil duct, in doing so, the oil feeds to and maintains a steady level at point of atomization.

What I claim is:

An oil burner nozzle comprising a one

piece metal element, an air duct near the top of the element, an oil duct located between the air duct and the base of the element, the air duct being of larger cross-section than the oil duct, an oil spray opening suitably located in the element, an open communication of small cross-section leading from the

air duct to the oil spray opening, means for maintaining a proper temperature on the burner consisting of a heating element suitably located in the nozzle. 10

In testimony whereof I affix my signature.

MERRITT AUGUSTUS WILLIAMS.
